UNITED STATES PATENT OFFICE.

CHRISTIAN F. HEINKEL AND WILLIAM G. LUETERS, OF CLEVELAND, OHIO.

SURFACING-MACHINE.

1,227,051.

Specification of Letters Patent. Patented May 22, 1917.

Application filed September 19, 1913. Serial No. 790,793.

To all whom it may concern:

Be it known that we, CHRISTIAN F. HEINKEL and WILLIAM G. LUETERS, citizens of the United States, both residing at Cleveland, in the county of Cuyahoga and State of Ohio, have invented a new and useful Surfacing-Machine, of which the following is a specification.

Our invention relates to improvements in surfacing machines in which an abrasive belt is brought to bear upon and smooth a surface.

The main object of our invention is an efficient and comparatively inexpensive machine. A number of minor and contributing objects will become obvious later in the specification and some of them will be pointed out particularly when describing the particular construction shown in the drawings.

We attain our objects by a novel arrangement and improvement of elements as is sufficiently illustrated in the accompanying drawings which show our invention embodied in a belt sander.

In the said drawings, Figure I is a front view of a belt sander embodying our invention; Fig. II is a side view of Fig. I; Fig. III is a section on line *a—a* of Fig. II; Fig. IV is a section on line *b—b* of Fig. I; Fig. V is a section on line *c—c* of Fig. I; and Fig. VI is a sectional view showing a matrix with rollers.

Similar reference characters refer to similar parts throughout the several views.

Our invention, conveniently titled surfacing machine, may be used for a variety of purposes, for instance, surfacing, smoothing, polishing, etc., of wood, metal, or other materials.

For the purpose of illustration, we have embodied our invention in the belt sander shown in the drawings, but wish to be understood that we do not limit ourselves to the particular construction shown.

Referring now particularly to the drawings: The base 1 is provided with the bosses 2 to which the housings 3 are bolted, with the bearings 4 which receive the shaft 5, and with the bearing surface 6 to which the gear case 7 is bolted.

At their lower portion, the housings 3 are provided with slides 8 and bearings 9 for the screws 10 and at their upper portion with surfaces 11 to which the guide bar 12 is bolted, with the surface 13 to

which the bracket 14 is bolted, and with the bearings 15 and 16. For the purpose of providing a large operating space for the table, the upper portion of the housings 3 are overhanging or form extensions. Since high vibrations are usually set up in a machine of this character, it is desirable that these overhanging extensions be connected so as to stiffen the machine. This object we accomplish by providing the brace 17 between these extensions. Further braces may be provided where found necessary, the object being to provide a machine which is rigid and as free from vibrations as possible when in operation.

In order to provide for a large capacity or operating space of the machine, and to do so economically, we form the overhanging arms or extensions directly on the housing 3 as distinguished from merely letting the pulleys overhang as at present. With our arrangement, a comparatively short machine may be employed to operate on long work which is also wider than the approximate width of the abrasive belt without turning the work end for end. Our arrangement also produces better work at less expense than heretofore since the surfacing is all done in one direction which produces a better finished article than surfacing in different directions could do, it being well known that surfacing in different directions shows plainly and detrimentally on a finished article. In the old machines it is necessary that long and wide work be turned end for end which requires a certain amount of floor space and labor and which necessitates that the work is piled some distance from the machine which requires that the operator must carry or convey the work a certain distance which also requires expense and labor.

In order to avoid all of the above disadvantages and produce a machine which requires less floor space than heretofore, which is more economical of first cost than heretofore, which is more economical of operation than heretofore, and which does better work than heretofore, we provide, among the other features herein set forth, that the upper portions of the housing 3 substantially overhang the table as shown.

For the purpose of providing up and down adjustment for the table, the saddles 18 are mounted on the slides 8 to slide up and down thereon. The nuts 19 are secured

to the saddles 18 and are adapted to receive the screws 10. At the upper portion, one saddle has a flat surface 20 while the other saddle has the V shaped surface 21; the object for such arrangement will appear hereinafter. These saddles should be well stiffened to prevent vibration of the table.

The shaft 5 fits rotatably into the bearings 4, has a bevel gear 22 secured to each end, 10 passes through and has bearings in the gear case 7, and has the worm wheel 23 secured thereon inside of the gear case 7.

The gear case 7 has bearing 24 into which the shaft 25 fits rotatably, and has a space 15 adapted to receive the worm 26 which is secured to the lower end of the shaft 25 and meshes with the worm wheel 23. The hand wheel 27 is secured to the upper end of shaft 25.

20 The screws 10 are threaded on their upper end and adapted to engage the nuts 19, fit rotatably into bearings 9, and have, at their lower end, the bevel gears 28 which mesh with the gears 22.

25 The table 29 has stiffeners 30 to which the rollers 31 and 32 are conveniently secured and is adapted to travel transversely by means of the rollers 31 and 32 and up and down by means of the screws 10 and their connecting mechanism. For the purpose of stiffening the table 29 lengthwise, the spacers 33 are secured to the under side of the table 29 and a lug 34 is provided on each end of the stiffeners 30. The lugs 35 are 30 provided on the lower end of each spacer 33 and the braces 36 connect the lugs 34 and 35. Adjustment may be provided on the braces 36 to facilitate manufacture and to take up wear. Such adjustment is common practice 40 and should be obvious. Similar braces may be provided on the table 29 to stiffen the same cross wise.

A satisfactory and easy method of mounting the guide rollers 31 and 32 is shown on 45 a larger scale in Fig. III. The guide rollers 32 have their outer circumference grooved and adapted to the V shaped surfaces 21 and have their inner opening provided with race ways 37 which are adapted to receive a series 50 of rolls 38 and may or may not have spacers therebetween as is common practice in roller and ball bearings. The studs 39 have race ways 40 which are adapted to the rolls 38 and also have the reduced portions 41 which 55 fit snugly into openings in the stiffeners 30 and are held therein securely by the nuts 42. The guide rollers 31 are similar to the guide rollers 32 except that the outer circumference is flat and adapted to the surfaces 20 60 whereas the guide rollers 32 are grooved and adapted to the surfaces 21; otherwise the general construction is the same. This arrangement is simple of construction since the inner race also forms the shaft and the 65 expense of forming separate sleeves and

shafts (as is common in such bearings) is eliminated, and furthermore the outer and inner races being much heavier than in the usual bearings, the danger of warping during the hardening process is lessened and, 70 consequently, less material need be allowed for grinding and, therefore, less expense incurred in grinding; and furthermore, these heavier parts will not break as easy as the lighter ones. All of which constitutes a 75 novel arrangement of elements which adds materially to the utility of the machine.

The shaft 43 fits rotatably into the bearings 15 and 16 on one of the housings 3 and has the pulley 44 secured to its front end. 80 The shaft 45 which is the driving shaft, fits rotatably into the bearings 15 and 16 on the other housing 3 and has the pulley 46 secured to its front end and the tight and loose pulleys 47 to its rear end.

85 The bracket 14 has a pin 48 upon which the lever 49 is fulcrumed. One end of this lever 49 carries the idler 50 and the other end carries the counterweight 51 which may be placed in a suitable position along the 90 lever 49 to give the belt the required tension and secured in such position by means of the set screw 52. The pulleys 44, 46, and 50 are in alinement.

95 Since it is desirable that a machine of this kind be adapted to operate over a large surface, we provide the traverse movement for the table 29 as hereinbefore described and we further provide the head A and adapt the same to travel along the guide bar 12. 100 In order to facilitate this travel, a number of antifriction guide rollers are mounted in the head A and in order to facilitate manufacture and to take up wear, these guide rollers are adjustably mounted.

105 The guide bar 12 has its edges beveled as clearly seen in Fig. IV and the outer circumference of the guide rollers 53 and 54 is arranged for a series of rolls similar to those shown in Fig. III and described in 110 connection therewith. The inner race has, in this instance, reduced portions 55 at each end instead of the one designated as 41 in Fig. III. One reduced portion 55 of the rollers 53 is mounted in the housing 56 of 115 the head A in proper relation with the guide bar 12 while the other reduced portion 55 is mounted in the housing 57 of the head A also in proper relation with the guide bar 12. One reduced portion 55 of the rollers 120 54 is mounted in the saddle 58 while the other reduced portion 55 is mounted in the bracket 59 which is secured to the saddle 58. The saddles 58 are mounted in the housing 56 as best seen in Fig. V and are held in position by means of the gib 60 and the screws 61.

125 It has been seen that the table 29 is provided with up and down movement or adjustment by means of the hand wheel 27 and 130

its connecting mechanism. This arrangement is for the purpose of adjusting the table to suit any particular work to be done by the machine. It is, however, desirable that some means be at hand whereby the abrasive belt 62 may be brought to bear upon or removed from the surface operated upon more readily than by adjusting the table itself which is generally cumbersome and requires extra time for operation particularly so when screws are used to tighten the saddles to the slides 8 which is commonly done and which we prefer to do. In order to save this time and produce an easy and rapid method of bringing the active surface of the belt 62 upon or away from the surface operated upon, the spindle 63 is mounted in the head A to travel up and down or longitudinally and, in order to reduce the friction and effort required for that purpose to a minimum, antifriction rollers are employed to bear against the spindle 63.

The spindle 63 is made of tubing and has four beveled surfaces 64 as best seen in Fig. V. To the lower end of the spindle 63 is secured the plug 65 to which the matrix holder 66 is hinged by means of the pin 67 as best seen in Fig. IV. When this machine is intended for polishing or similar purposes, this matrix holder 66 may swivel traversely to the travel of the belt 62 so that the matrix 68 may adjust itself crosswise to any inequalities which may occur when a number of pieces are operated upon successively since it is well known in the art that it is practically impossible to manufacture a number of pieces so near alike that a rigid head will smooth the surfaces properly without removing an excessive amount of material which requires a certain amount of time; the swivel matrix holder which we provide saves this time. When, however, the machine is intended to surface a number of pieces successively and all to the same size and shape, the matrix holder should be rigidly secured to the spindle which may be accomplished by any of the well known means of clamping the matrix holder to the lug. To insure even thicknesses of the pieces operated upon we provide the stop collar 69 which may be set to any required position, preferably by clamping it to the spindle 63, since a set screw may mar the surface of the spindle and cause it to stick when it comes under the guide rollers. Instead of the spindle 63 being made of round tubing and flattened as shown, it may be made of square or other shaped tubing; the object being to prevent the spindle 63 from turning so that the matrix will always retain its proper position since the lower surface of the matrix may have an irregular contour as for instance in moldings and any turning of the spindle may destroy the

required shape of the article operated upon. Another object being to make the spindle as light and sensitive as possible; this we accomplish by using tubing for the spindle.

In order to prevent the aforesaid turning of the spindle 63 and to provide for easy movement thereof, the guide rollers 70 and 71 are provided with their outer circumference grooved to suit the bevel surfaces 64 of the spindle 63 as best seen in Fig. V and with their inner portion arranged to receive a series of rolls similar to the rolls 38 seen in Fig. III. The inner races also being similar to the stud 39 except that the reduced portions 72 are provided on each end whereas the stud 39 of Fig. III has one reduced portion 41 only. One reduced portion 72 of each roller 70 is mounted in a saddle 73 while the other reduced portion 72 is mounted in the bracket 74 which is secured to the saddle 73. The saddles 73 are held in position in the head A by means of the gibs 75 and are moved for adjustment by means of the screws 76 as best seen in Fig. V, the saddles 58 being likewise moved for adjustment by means of the screws 77, a suitable slideway for the saddles 58 and 73 being provided in the head A.

One reduced portion of each guide roller 71 is mounted in the housing 56 of the head A while the other reduced portion 71 is mounted in the housing 57 of the head A.

The object of mounting the saddles as shown is to provide adjustment for the rollers in two directions at right angles with each other. With such arrangement it is not necessary that all of the parts be machined accurately, it is quite an undertaking to machine the parts sufficiently accurate and quickly so that the rollers will bear evenly and nicely upon the surfaces of the spindle. Adjustment in one direction is accomplished by the screws 76 and 77 as hereinbefore described whereas adjustment in the other direction is accomplished as follows: When loosening the screws 61 (Fig. V) of the left hand side for instance and tightening the screws 61 on the right hand side, the roller will be shifted toward the left hand side. When the rollers are to be adjusted traversely to the adjustment just described, the slides should be arranged at right angles to the arrangement shown in the drawings which are intended to show our invention generally. This modification, as well as many others, is thought obvious to those skilled in the art and to need no detailed description or drawing since the drawings show sufficient mechanism to illustrate our invention.

In order to move the spindle 63 up and down or longitudinally, the housing 57 of the head A has two ears 78 between which the lever 79 is hinged by means of the pin 80 and the plug 65 has an ear 81 to which

the connecting rod 82 is hinged by means of the pin 83. The other end of the connecting rod 82 being hinged to the lever 79 by means of the pin 84.

- 5 In order to prevent the spindle 63 from moving down by gravity and bring the abrasive belt in contact with the table or with the material then on the table, the spring 85 is provided inside of the hollow 10 spindle 63. The upper end of the spring 85 being secured to the spindle 63 by means of the pin 86 and the lower end being secured to the housing 57 of the head A by means of the pin 87. In order to permit 15 the spindle 63 to travel longitudinally when the pin 87 is in position, *i. e.* passing through the spindle in order to find lodging in the housing, the slot 88 is provided in the spindle 63.
- 20 In order to reduce friction, the matrix may be provided with a series of rolls which are formed with the required contour. Such arrangement is shown in Fig. VI where the matrix 68^a carries a series of 25 rollers 89. In order to reduce friction still further, these rollers 89 may be provided with antifriction bearings similar to the guide rollers previously shown and described.
- 30 The belt 62 has abrasive material upon its outer surface which abrasive material may constitute sand and glass as generally used for wood working or emery or carb-35 rundum or other material as used for metal working or any other suitable material for the above or other purposes. Such an endless belt which gives good results may readily be made of sandpaper or emery paper or emery cloth by removing the abrasive material from a suitable distance at 40 one end of a strip of such paper or cloth of the required or necessary length to pass over the pulleys and lapping the ends and gluing them together; care being taken so 45 that the inside lap runs with the direction of the belt travel as is well known in the construction of endless belts. The belt 62 passes over the pulleys 44 and 46 and 50 and also over the matrix 68 for which purpose all of these elements should be in alignment.

55 Since a machine of this kind produces considerable dust, it is desirable that an exhaust fan (not shown in the drawings) be employed and that all moving parts be protected as much as possible. In the head A this may be done by placing all of the guide rollers inside of the housing as indicated in the drawings. As a further precaution, 60 brushes may be applied or secured to the machine at suitable positions or wherever found necessary or advisable, to brush off whatever dust may have collected on exposed parts before the moving parts pass 65 thereover. This brush arrangement is

thought obvious without further drawing or description.

The section of the upper and rear portion of Fig. IV is taken somewhat back of line *b*—*b* to show the arrangement of the 70 saddle, gibs and housing.

The operation of the machine shown in the drawings is as follows: The endless and abrasive belt 62 being placed over the pulleys and matrix as set forth and a source of power being applied to rotate the shaft 45 as for instance a belt on the pulleys 47, the abrasive belt is set in motion and travels over the pulleys 44, 46, and 50 and over the matrix. The material to be operated upon is placed upon the table 29 which is then adjusted to a convenient height by means of the hand wheel 27 which rotates the shaft 25 and the worm 26 whereby the worm wheel 23 and the shaft 5 and the 85 gears 22 are rotated which in turn rotate the gears 28 and the screws 10; when the desired height of the table elevation is reached, the saddles 18 are clamped in position. Traverse adjustment of the table 90 is accomplished in this instance by merely pushing the table to the desired position horizontally for which purpose the top portion of the saddles is made long as shown in the drawings. The table being prevented 95 from displacement by the beveled surfaces 21 and yet will not bind and will always move freely owing to the flat surface 20 which permits of variation between the surface 20 and the rollers 31 whereby ease of 100 manufacture (the parts need not be machined accurately) is attained and wear of the slides and bearings may be taken up without disturbing the free movement of the table. The spindle 63 is held up and 105 out of the way by the spring 85. Now take hold of the lever 79 and pull outward and downward. The lever 79 being hinged to the housing, will fulcrum on the pin 80 and cause the pin 84 to travel on this fulcrum 110 whereby a downward movement is given to the connecting rod 82 and also to the spindle 63. When the spindle is so moved down and the abrasive belt touches or is pressed upon the surface to be smoothed, the lever 115 79 will stand outward from the head A which is then moved along the bar 12 by pushing the same lever 79 back and forth longitudinally as required. When the head A is so moved, the matrix also moves with 120 it and the surface over which it moves will be smoothed. When the work is completed, the lever 79 is released or pushed up and will be held in the upper position shown in the drawings by means of the spring 85. 125 When a surface wider than the matrix is to be smoothed, the lever 79 may be operated by one hand and the table 29 moved traversely by the other hand. When the spindle 63 is operated up and down, the belt 62 130

will likewise be moved where it passes over the matrix 68. The pulleys 44 and 46 being fixed in position and the belt 62 being fixed in length, the pulley 50 will fulcrum on the pin 48 and move up and down in accordance with the movement of the spindle 63. The weight 51 being set in proper position on the lever 49 to facilitate such movement and to provide the required tension on the belt 62. The guide rollers are adjusted by manipulating the screws 76 and 77 and the gibs 60 and 75 as hereinbefore set forth.

The construction and operation of the machine shown in the drawings should now be clear.

We will now add a few general remarks which will further explain our invention and help to understand the same.

Our invention aims to produce a machine which has a wide range of operation, in which the manual labor for operation is reduced to a minimum, which has a long life, and in which the operating members are in convenient positions for the operator and are made light in weight. We accomplish our aim by new and novel arrangements and combinations of old elements with new ones or improved ones as shown in the drawings and described in connection therewith and as indicated, generally, by the following suggestions for modifications:

In order to reduce friction, all moving parts may be provided with antifriction bearings instead of those shown in the drawings. In order to prolong the life of the machine, all bearings may be made adjustable. The drawings show alternate guide rollers provided with adjustable bearings but all of the guide rollers may have such bearings. The spindle, matrix, and operating levers should be as light as possible in order to provide ease of operation and sensitiveness for operation. The overhanging arms on the housings should be as stiff as possible to prevent vibration of the machine. The table may also be provided with traverse braces similar to the longitudinal braces shown in the drawings. A rack may be secured to one of the saddles or to the housing and a pinion mounted on the table for hand operation and to mesh with the rack for traverse feed of the table. A suitable clamping arrangement may be provided to clamp the table in any traverse position. Guides may be placed on the table so that a number of pieces to be operated upon may be placed thereon successively in the same position with relation to the matrix. The head A may be omitted, in which case the operator holds the matrix in his hand and moves it along the surface to be smoothed. Automatic feed in both directions may be provided for the head A together with automatic feed reverse either at each end of the guide bar or at any point intermediate the ends.

It is thought that the scope of our invention is now fully understood.

Without limiting ourselves to the particular construction shown and described, we claim:

1. In a surfacing machine, the combination of a housing, two rotatable shafts on the housing, a pulley on the front end of each shaft, an abrasive belt over the pulleys, means for taking up the slack in the belt, 70 a guide bar with beveled edges secured to and connecting the housing near the top, a head to travel lengthwise on the bar, four rollers mounted in the head and having a V shaped circumference, each roller engaging two of the beveled edges to prevent lost motion of the head both traversely and vertically, a matrix mounted in the head and adapted to press the abrasive belt upon the work, a table, means for operating the table, 80 and means for operating the abrasive belt.

2. A surfacing machine having a bed and a housing, a table mounted thereon, two arms projecting from the housing and overhanging the table to permit of work longer than 90 the machine to be operated upon, a guide bar with beveled edges secured to and connecting the arms, a head to travel longitudinally on the guide bar, four rollers with a V shaped outer circumference mounted in 95 the head, each roller engaging two of the beveled edges to prevent vertical and traverse movement of the head, a rotatable shaft mounted on each arm, a pulley on the front end of each shaft, an abrasive belt 100 over the pulleys, a matrix mounted in the head and adapted to press the abrasive belt upon the work, means for taking up the slack in the belt, and means for operating the belt and the table.

3. A surfacing machine having a bed and housing, a table mounted thereon, two arms projecting from the housing and overhanging the table to permit of work longer than 105 the machine to be operated upon, a guide 110 bar with beveled edges secured to and connecting the arms, a head to travel longitudinally on the guide bar, four rollers with V shaped outer circumference mounted in the head, each roller engaging two of the 115 beveled edges to prevent vertical and traverse movement of the head, a second set of four rollers with V shaped outer circumferences mounted in the head, a spindle with four flat and longitudinal surfaces between 120 the last mentioned rollers, each roller engaging two of the flat surfaces to hold the spindle in alinement and prevent rotation thereof, a matrix on the end of the spindle, a rotatable shaft on each arm, a pulley on 125 the front end of each shaft, an abrasive belt over the pulleys and the matrix, means for taking up the slack of the belt, and means for operating the matrix and the table and the belt.

4. The combination of a guide bar having beveled edges with a head having rollers formed to engage the beveled edges for the purpose set forth and having a spindle with flat longitudinal surfaces and rollers formed to engage the flat surfaces for the purpose set forth.
5. In a surfacing machine, the combination of a bed and housing thereon, a guide bar secured to the housing, a head suspended upon the guide bar, a spindle in the head, a plurality of flat surfaces longitudinally on the spindle, a plurality of guide rollers bearing against the spindle, the outer circumference of each guide roller formed to engage two of the flat and longitudinal surfaces on the spindle, the inner circumference of each guide roller forming the outer race for a series of rolls, a stud for each 10 guide roller mounted in the head and forming the inner race for the rolls, a series of rolls between the inner and outer races, a matrix on the spindle, means for operating the spindle, an abrasive belt passing over the aforesaid pulleys and over the matrix, a source of power to operate the belt, a movable table, and means for operating the table.
6. The head A having a set of guide rollers, the outer circumference of these guide rollers formed to engage a guide from which the head is suspended, the inner circumference or recess of the guide rollers forming the outer race for a series of rolls, a stud for each of the guide rollers mounted in the head and forming the inner race for the rolls, and a series of rolls between each inner and outer race.
7. In a surfacing machine, the combination of a guide bar having beveled edges, and head suspended from the guide bar and having rollers, and each roller formed to engage two of the beveled edges.
8. In a surfacing machine, the combination of a head, a spindle having longitudinal flat surfaces in the head, each two flat surfaces at an angle with each other, a set of rollers in the head, each roller formed to engage two of the flat surfaces, and means for adjusting the rollers in relation to the spindle.
